COVER CLAMP FOR ELECTRICAL APPARATUS

Edward D. Treanor, Pittsfield, Mass., assignor to
General Electric Company, a corporation of
New York

Application August 31, 1935, Serial No. 38,766. Filed Oct. 22, 1935.

3 Claims. (Cl. 220—55)

My invention relates to cover clamps for electrical apparatus casing and is particularly applicable in connection with clamps for holding securely in position the covers of casings of such 5 electrical apparatus as transformers which are immersed in insulating oil or other liquid. The cover of a casing for liquid immersed transformers or other similar electrical devices should be held securely and tightly in place during normal 10 operation of the enclosed electrical apparatus in order to protect the apparatus from outside dirt and moisture, but it is desirable that any means used for this purpose be not only effective and reliable but also of such construction that the 15 cover may be quickly and easily released and the casing opened for inspection or other purposes. The general object of the invention is to provide an improved cover clamp having these desirable features.

20 The invention will be better understood from the following description taken in connection with the accompanying drawing, in which Fig. 1 is a view of the upper part of a transformer casing with its cover secured in normal closed position by cover clamps constructed in accordance 25 with the invention; Figs. 2 and 3 are views similar to that shown in Fig. 1, but with the cover clamps loosened and the cover held in raised position by the clamps; Fig. 4 is a view of a fragment of the 30 transformer casing with the cover clamp partially loosened; and Fig. 5 is a view similar to that shown in Fig. 4, but with the cover clamp loosened and tipped away from the cover to permit the cover to be raised.

35 Like reference characters indicate similar parts in the different figures of the drawing.

The transformer casing 10 shown in the drawing has a cover 11 fitting over the upper edge of the side wall of the casing.

40 As shown in the drawing, a pair of bushings 12 extend through the cover 11 to insulate the high voltage leads from the transformer. The upper part of a side pocket for insulating bushings for the low voltage transformer leads is also shown.

45 The cover 11 is normally held tightly in closed position, as shown in Fig. 1, by cover clamps 13, two such clamps being shown, although a larger number may be provided, if it is desired, particularly for a cover of large size.

50 Each cover clamp 13 includes a lug 14 welded or otherwise secured to the outer face of the side wall of the casing 10 just below its upper edge. This lug 14 has parallel spaced sides 15, with the inner part of their lower edges cut away or 55 notched for engagement by lifting cables, such

as are frequently used during handling for shipment. The clamp 13 further includes a rod 16 with its lower end secured by a pivotal connection 17 between the sides 15 of the lug 14. A wing nut 18 is threaded onto the upper or outer end 5 of the rod 16. A holding member 19 has a cylindrical body portion 20 which may slide freely on the rod 16. An upward extension 21 from the body portion 20 of the holding member is bent over at its outer end to fit over the edge of the 10 cover 11 of the casing 10. A helical spring 22 is provided on the rod 16 between the wing nut 18 and the body portion 20 of the holding member 19.

With the cover 11 in closed position and the 15 holding member 19 held close to the outer edge of the cover, the cover may be secured in normally closed position by tightening the wing nuts 18 of the cover clamps so as to draw the curved or hooked shaped upper ends of the holding members 19 tightly down onto the cover. There may be, in some cases, a tendency for the holding members to be pulled laterally away from the cover and slip off its edge. This is effectively prevented by side flanges 23 on the holding member 19 arranged to engage in notches 24 in the upper edges of the sides 15 of the lugs 14. These flanges 23 and the outer side edges of the notches 24 are inclined slightly upwardly and outwardly with respect to the rod 16 so that as the holding member 19 is forced down into holding position on the edge of the cover 11, the holding member will at the same time be drawn in toward the cover and any disengagement of the holding member from the cover effectively prevented. Fig. 1 of the drawing shows the cover 11 of the transformer casing held securely in place by two clamps 13 with the side flanges 23 engaged in the notches 24 to prevent accidental disengagement of the clamps. Fig. 4 shows a cover clamp 40 partially loosened and its side flanges 23 disengaged from the notches 24. Fig. 5 shows a clamp 13 pulled laterally away from its cover 11 about its pivotal connection 17 with the lug 14 so that it is free of the cover and the cover may be easily 45 raised.

Under normal operating conditions of the transformer, it is desirable that the clamps 13 hold the cover 11 securely in place to exclude outside dirt and moisture, but there is always a 50 possibility that excessive pressure may develop inside the casing 10 due to a fault in the transformer such as a breakdown of insulation. If such pressure becomes so high as to be dangerous, the springs 22 will yield and allow the cover 55

11 to open slightly so as to relieve the pressure and prevent an explosive rupture of the casing 10.

Many transformers are mounted high above the ground on poles or in other positions which are not very easily accessible. It is, however, often necessary that such transformers be inspected or repaired. As shown in Fig. 3, the cover 11 is pivotally connected at one edge to the side 10 of the casing 10 by a link 25. The wing nuts 18 have notches 26 in their upper edges. When the cover 11 is raised as shown in Figs. 2 and 3, the clamps 13 may be pulled in toward the casing with the notches 26 under the edge of the cover 15 to engage it and hold the cover in raised position while the transformer is inspected or repaired. The outer edge of the cover 11 is formed with a flange which fits easily into the notches 26 so that the clamps cannot slip out of place accidentally and allow the cover to drop.

The invention has been explained by describing and illustrating a particular embodiment thereof, but it will be apparent that changes may be made without departing from the spirit of 25 the invention and the scope of the appended claims.

What I claim as new and desire to secure by Letters Patent of the United States is:

1. The combination with an electrical apparatus casing having a cover, of a lug secured to the side of the casing below its cover, a holding member for engaging the cover, and means pivoted to

the lug for tightening the holding member onto the cover, the lug being formed with a notch, and the holding member having a flange arranged to engage in the notch of the lug when in tightened position to prevent lateral motion of the holding member away from the cover.

2. The combination with an electrical apparatus casing having a cover, of a lug with spaced sides secured to the side of the casing below its cover, a holding member for engaging the cover, and means pivoted to the lug between its sides for tightening the holding member onto the cover, the sides of the lug having notches in their upper edges, and the holding member having side flanges arranged to engage in the notches of the lug when in tightened position to prevent lateral motion of the holding member away from the cover.

3. The combination with an electrical apparatus casing having a cover, of a lug with spaced 20 sides secured to the side of the casing below its cover, a holding member for engaging the cover, and means including a rod pivoted to the lug between its sides for tightening the holding member onto the cover, the sides of the lug having 25 notches in their upper edges, and the holding member having side flanges inclined to the rod and arranged to engage in the notches of the lug when in tightened position to prevent lateral motion of the holding member away from the 30 cover.

EDWARD D. TREANOR.
